UNITED STATES PATENT OFFICE

2,182,698

CIGARETTE MAKER

Hugh Forrester Kirkwood, Bucksport, Maine

Application March 13, 1939, Serial No. 261,579

2 Claims. (Cl. 131—5)

The invention relates to a cigarette maker and more especially to a novelty device for cigarette making.

The primary object of the invention is the provision of a device of this character, wherein cigarette paper held within a pack can be conveniently carried and each sheet or wrapper of cigarette paper can be rolled in a convenient manner and placed in a position to be readily and easily filled with tobacco so that a complete handmade cigarette can be had without liability of waste of the tobacco when filling the cigarette paper or wrapper for the making of the cigarette.

Another object of the invention is the provision of a device of this character, wherein the tobacco can be packed within a cigarette paper or wrapper and the latter completely filled without waste of the tobacco during the filling or packing period and in the use of such device a handmade cigarette results therefrom without necessitating excessive labor on the part of the user or operator of the device.

A further object of the invention is the provision of a device of this character, wherein a pack of cigarette papers can be held therein and the device conveniently carried on the person, being compact and susceptible of handy operation for the hand making of cigarettes and the resultant product having the appearance of a machine made cigarette.

A still further object of the invention is the provision of a device of this character, wherein the rolling of the papers as wrappers for cigarettes can be accomplished with ease and dispatch without liability of mutilating or otherwise disfiguring the papers and when rolled can be conveniently filled with tobacco, particularly the granulated kind, for effecting handmade cigarettes.

A still further object of the invention is the provision of a device of this character, which is simple and novel in construction, thoroughly reliable and efficient in operation, susceptible of being carried on the person, easy of manipulation, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an exploded perspective view show-

ing the device constructed in accordance with the invention with the pack of cigarette papers removed therefrom.

Figure 2 is a longitudinal sectional view through the device.

Figure 3 is a sectional view taken on the line 3—3 of Figure 2 looking in the direction of the arrows.

Figure 4 is a sectional view taken on the line 4—4 of Figure 2 looking in the direction of the arrows.

Figure 5 is a perspective view of a mandrel constituting an adjunct together with a capping element of the device.

Similar reference characters indicate corresponding parts throughout the several views in the drawing.

Referring to the drawing in detail, A designates generally a pack of cigarette papers and is conventional, the papers being singly drawn or pulled from the pack for the making of a cigarette while B denotes generally the device for the making of the cigarette and constituting the present invention as hereinafter fully described.

The device B comprises a casing 10 preferably made from sheet metal having built therewith at one longer edge a partially cylindrical or tubiformed trough 11 while at the opposite or other longer edge is formed a clip 12, then at one end is a closure wall 13, the other end being open so that the pack A can be introduced through this open end into the casing 10 and held against the wall 13 by the clip 12 so that said pack A by the clip is retained within the casing for easy removal of the pack at will. The trough 11 has permanently fitted therein a longitudinally slotted cylindrical barrel 14, being extended for a distance within said trough and open at opposite ends. The slit in the barrel 14 is indicated at 15, and the open end inwardly of the trough 13 of this barrel carries a mouth piece 16 having a flared mouth 17 which opens directly into the trough 11 and the latter opens into the casing 10, the latter partially opened at one side, that is, the side next to the trough, so that tobacco can be poured into the casing and gravity flow thereof had in the direction of the trough 11 for a purpose presently described.

The trough 11 has an outwardly bent lip edge 18 extending longitudinally for a major extent 50 thereof while the remaining edge 19 overlaps the pack A when stored within the casing 10. The lip 18 assists in the gravity flow of the tobacco, denoted at 20, from within the casing 10 into the trough 11 so that the tobacco within this trough 55

can be fed through the mouth 16 into the barrel 14 in a manner and for the purpose presently described.

- 5 Fixed on the casing 10 exteriorly thereof at the back of the same are spaced eyes 21 for removably receiving a mandrel 22 of uniform circular cross section throughout its length excepting the outwardly tapered tip 23 thereof. This mandrel 22, when removed from the eyes 21, is of 10 a cross sectional size to be accommodated within in the barrel 14, and such mandrel is for the purpose of rolling cigarette paper 24 thereon for creating a cigarette wrapper and also for the placement of the said mandrel with the wrapper 15 24 rolled thereon into the barrel 14. Upon the placement of the rolled wrapper 24 within the barrel 14, the mandrel 22 can be readily extracted from the rolled wrapper leaving the said wrapper in the rolled condition within the barrel for the 20 reception of the tobacco 20 in the making of the handmade cigarette. The wrapper 24 in the rolled condition is fully within the barrel 14 with the outermost end of the rolled wrapper flush with the outer end of said barrel while the inner 25 end of the rolled wrapper is protected by the mouth 16, which has a nipple 25 adapted to be telescoped into the inner end of the rolled wrapper when within the barrel for protection to said wrapper at this end.
- 20 The wrapper 24, when completely rolled upon the mandrel 22, has the outermost longer edge thereof tacked to avoid the unrolling of the wrapper from completed rolled condition.

- 30 Slidably fitted on the mandrel 22 and removable therefrom when desired is a capping member 26, its partial sleeve formation 27 being telescopically engaged over the barrel 14 for closing the outer end of the latter and retaining the wrapper 24 within said barrel in its rolled condition. The capping member 26 is applied to the barrel after removal of the mandrel from the wrapper 24 when the latter is confined in a 35 rolled condition within the barrel.

35 The trough 11 at the end remote from the barrel 14 is formed with a reduced tubular throat extension 28 through which plays a feeder spiral 40 29. This spiral 29 has a turning grip 30 swiveled upon a crank 31 of a slide rod 32 movably fitting upon a crank 31 of a slide rod 32 movably fitting 45 33. These eyes or sleeves 33 are built externally on the trough 11, and this feed spiral 29, when rotated, urges the tobacco within the trough 11 through the mouth 16 into the wrapper 24 rolled and held within the barrel 14. When the fed tobacco packs within the 50 55 wrapper 24, the feed spiral 29 is caused to retract within the trough 11 through the throat 28, the rod 32 slidably fitting the eyes or sleeves 33 following the retracting movement of the said spiral. In this manner the cigarette 60 is handmade.

65 When the mandrel 22 is not in use, the same is engaged in the eyes 21 and the capping piece carried by this mandrel when not in use will cap the end of the barrel 14, as is clearly shown in Figure 1 of the drawing. Also the pack A, when the device is not in use, is held within the casing 10. However, it is not required that the pack A be fully removed from the casing A when making a cigarette because such pack can be 70 utilized as disclosed by dotted lines in Figure 2 of the drawing to close the open end of said casing and in this position the tobacco sifted from the back or the like into the casing 10

can not drop or be wasted through the open end of said casing due to the occupancy of the pack therein. The mandrel 22 when in the eyes 21 and also the rod 32 slidably fitting the eyes or sleeves 33 are disposed parallel with each other and also parallel with the trough 11 and barrel 14.

5 The assembled relationship of the parts of the device renders the same compact.

10 The tip 23 of the mandrel 22 enables the easy insertion of the mandrel within the barrel 14 through the outer open end thereof when the cap 26 is removed from this end. The slot 15 in the barrel 14 is provided to allow the mandrel to be inserted within said barrel with a cigarette paper partially wound thereon and the edge of the exposed portion of this paper can be wetted and by the turning of the mandrel telescoped within the barrel the paper will be completely rolled within the barrel and its wetted end tacked 15 20 for maintaining rolled condition of the paper.

15 The feed spiral 29 freely operates through the mouth 16 and the throat 28 being manually turned at the grip 30 for feeding operation thereof in advancing the tobacco 20 in the trough 11 into the rolled cigarette paper 24 when confined within the barrel 14 of the device. As the tobacco packs within the roll, the spiral 29 backs outwardly therefrom allowing the wrapper or cigarette paper 24 in its rolled condition to be 25 fully and completely filled with the tobacco and the latter properly packed therein. When the cigarette has been completed, the cap 26 is removed from the outer end of the barrel and the said completed cigarette can be ejected from the device by the feed spiral 29, the latter being 30 pushed inwardly through the throat 28 and mouth 16 hereinbefore referred to.

35 What is claimed is:

1. A cigarette making machine comprising a 40 casing for receiving loose tobacco, a trough opening into the casing for the flow of tobacco therein, a barrel aligned with the trough and in communication therewith and adapted to receive a rolled cigarette wrapper, releasable capping means for fitting the barrel to retain the wrapper 45 therein, a turnable feed spiral for delivering the tobacco into the wrapper from the trough and displaceable relative to the latter, a slide for the spiral associated with the trough, a mandrel for the rolling of the wrapper and removably received in the barrel, means for hanging the mandrel to the casing, and means for removably fitting the capping means on the mandrel.

2. A cigarette making machine comprising a 55 casing for receiving loose tobacco, a trough opening into the casing for the flow of tobacco therein, a barrel aligned with the trough and in communication therewith and adapted to receive a rolled cigarette wrapper, releasable capping 60 means for fitting the barrel to retain the wrapper therein, a turnable feed spiral for delivering the tobacco into the wrapper from the trough and displaceable relative to the latter, a slide for the spiral associated with the trough, a mandrel for 65 the rolling of the wrapper and removably received in the barrel, means for hanging the mandrel to the casing, means for removably fitting the capping means on the mandrel, and a turning grip formed with the spiral and swiveled 70 to the slide.

HUGH F. KIRKWOOD.
